OBERLIN SMITH, OF BRIDGETON, NEW JERSEY, ASSIGNOR OF ONE-HALF TO
GEORGE DRAPER & SONS, OF HOPEDALE, MASSACHUSETTS.

WARP STOP-MOTION FOR LOOMS.

SPECIFICATION forming part of Letters Patent No. 515,536, dated February 27, 1894.

Application filed June 12, 1893. Serial No. 477,342. (No model.)

To all whom it may concern:

Be it known that I, OBERLIN SMITH, of Bridgeton, county of Cumberland, State of New Jersey, have invented an Improvement

5 in Warp Stop-Motions for Looms, of which the following description, in connection with the accompanying drawings, is a specification, like letters on the drawings representing like parts.

10 This invention relates to warp stop motions for looms, in which the breakage or slackening of a warp thread is detected by the difference in tension upon the heddle through which it passes.

15 The object of this invention is to provide simple and reliable mechanism by which the loom may be stopped when the tension of any particular warp thread or threads upon its heddle or heddles is not as great as it 20 should be.

In carrying out this invention I provide a series of heddle heads, which, when thread 25 heddles are used, are formed independently of the heddles and moved thereby, but which when wire heddles are used are formed preferably by the ends of the heddles themselves, which heads are moved at each formation of a shed by the tension of the warp threads when moved by said heddles into one or the

30 other plane of that shed. Each heddle frame is provided with a feeler which is moved toward and from the heddle heads of that frame, the range of movement of such feelers being varied by the positions of the heddle heads.

35 Co-operating with the several independent feelers on the respective heddle frames, and constituting one of the principal features of this invention, is a single master-feeler which stands at the end of the loom 40 and co-operates with the feelers on the heddle-frames, which thereby control the movements of the master feeler at the end of the loom, the latter controlling the stop-motion. In the preferred construction I have also pro-

45 vided a suitable connection moved or controlled by this master feeler at the proper time, and interposed between a lug on the weft or other slide-bar which actuates the stop-motion, and a moving part of the loom, 50 whereby the said moving part through said

connection moves the lug and stops the loom without throwing any stresses or work of any sort upon the more delicate parts of the stop-motion.

Other features of this invention will be 55 hereinafter more fully set forth in the specification and claims.

Figure 1 of the drawings represents in vertical cross section, a loom equipped with a stop-motion embodying this invention; Fig. 60 2, a section on an enlarged scale of the essential working parts of Fig. 1; Fig. 3, a partial face view looking from the left of the parts shown in Fig. 2; Figs. 4 and 5 similar views to Figs. 2 and 3, but showing the parts in 65 different position, or in the positions they will assume when stopping the loom; Figs. 6, 7 and 8, enlarged sectional details of parts of a heddle frame showing the co-operative movement of one of the auxiliary feelers with 70 the heddle-heads; Fig. 9, a detail showing the manner of actuating an auxiliary feeler; Fig. 10, a sectional detail illustrating a modified construction to be described; Fig. 11, a cross sectional detail of the swinging lever o' , 75 showing its forked or recessed end to be described and Fig. 12, a detail showing a modification of heddle head to be described.

Referring to the drawings, A represents a portion of the end frame of a loom; B the 80 lay or crank-shaft; C the lay; C^x the lay-sword operated from said shaft; C^y the breast-beam; C^z a weft-fork; C^t a weft-slide bar; C^s a weft-hammer; C^g a cam on the shaft C^{10} to actuate the said weft-hammer; f^4 a rock-shaft 85 having an arm f^3 adapted to be engaged and moved by the weft slide-bar C^t , and an arm f^5 adapted to push the shipper, not shown, from its notch and effect the stopping of the loom, all of which are and may be of any well 90 known or desired construction and arrangement, actuated in usual manner, and need not therefore be herein further described either as to their construction or operation.

D, D' , represent the heddle frames or carriers for the heddles through which the warp threads are passed, which heddles, so far as this invention is concerned, may be of either thread or wire, or in fact of any other suitable or desired form. I have, however, in the 95 100

principal figures of the drawings, elected to illustrate my invention as used in connection with the usual thread heddles.

Referring to Figs. 2 and 3, the heddle frames D, D', consist of upper and lower frame bars d, d', together with an intermediate bar d^x located parallel with and near to the upper frame bar d. The thread heddles h having eyes h', through which the warp threads w are passed, are, at their lower ends, passed about or otherwise secured to the lower frame bars d' of the heddle frames, and at their upper ends said heddles are attached or hooked to the lower ends of the pins e, see Figs. 2, 6 and 8, fitted to slide vertically in the intermediate bars d^x of the heddle frames, the said pins at their upper ends being provided with heads e² which constitute one form of heddle-heads connected with the heddles 20 and moved by the varying tension of the warp threads thereupon.

Referring to Fig. 8, the springs e³ surrounding the pins e, and acting at their upper ends against the heads e² thereof, act to move the heads normally into their elevated positions thereby maintaining the heddles taut.

Each heddle frame is provided, as shown best in Figs. 6 to 8, with a feeler m, herein after termed an auxiliary feeler, to distinguish it from a master feeler to be described, said auxiliary feeler being pivoted at its ends in the vertical end bars of the frame, and is adapted to be moved about its axis, and caused to sweep across the paths of movement of the heddle heads of that frame, clearing the said heads when the latter are drawn down into their lowermost positions, as in Fig. 6, but encountering and being stopped by any one of said heads permitted to remain in its elevated position, as shown in Figs. 7 and 8. Each auxiliary feeler m has secured to its pivot at one end of and outside its frame, an arm m', see Fig. 9, which preferably extends in a direction substantially at right angles to the feeler, said arm in the present construction in turn having a finger m² leading from it at right angles or in a direction substantially parallel with the feeler m, said arm m' at its outer end having an eye through which is passed the end of a feeler actuating rod m³ extended downwardly, as shown in Fig. 5, and at its lower end secured to some fixed support, as, for instance, the frame of the loom, a spring m⁴ being interposed in and preferably forming a part of this actuating rod m³. From this it will be seen that whenever a heddle-frame is raised, carrying with it the feeler m, the actuator m³ attached to a fixed support at its lower end will act to pull the arm m' down, and thereby turn the feeler on its pivot and cause it to sweep across the paths of movement of the heddle-heads in that frame, the spring m⁴ interposed in the actuator permitting the heddle frame to be at all times raised whether or not the feeler is permitted to partake of its full movement. A spring m⁵ also attached to the outer end of the arm

m', and at its upper end to the heddle frame, serves to return the feeler to its normal position upon the descent of the heddle-frame.

By reference to Figs. 6, 7, and 8, it will be seen that the finger m² stands in a vertical position only, when the feeler is in its position, Fig. 6, it having been moved through the entire range of its movement, and that whenever the feeler is stopped by either of the heddle-heads it leaves the said finger in an angular position, as shown in either Fig. 7 or Fig. 8.

Referring particularly to Figs. 1 to 5, N represents what I term a master-feeler, the same being arranged in a position substantially at right angles to the auxiliary feelers m, and journaled at its ends in suitable bearings n carried by one of the end frames of the loom, 85 said master feeler, opposite the ends of the heddle frames, having the depending plate portion n' in which are cut several vertical slots n², there being a slot for each heddle frame, said slots being located in such positions with relation to the said heddle frames and the fingers m² mounted thereon, that when the said fingers stand in substantially vertical positions, as in Fig. 6, the said master-feeler may be swung on its pivots toward the ends of the heddle frames, the fingers passing through the vertical slots m² in the said master feeler, but when the said fingers are in their positions Figs. 7 and 8, they cannot enter said slots and will therefore interrupt and stop the movement of the master-feeler.

The master feeler is moved by oppositely extended arms n³, n⁴, see Figs. 3 and 5, to which are connected the actuating rods n⁵, n⁶, leading downwardly and connected with the 105 ends of the oppositely extended arms n⁷, n⁸, see Fig. 1, on the lower pivoted end of the lay sword, so that when the latter is rocked to carry the lay forward and back the movements of the arms n⁷, n⁸, will act through the 110 rods n⁵, n⁶, to communicate a rocking movement to the master feeler, causing the latter to move toward and from the heddle frames at each pick. The actuating rods, as herein shown, have interposed between their ends, 115 springs n⁹, n¹⁰, which yield when the master feeler encounters and is stopped by one of the fingers m², or otherwise. To the forward end of the master feeler N is pivoted at o the swing-bar o', counterweighted at o², and maintained thereby in a normal inclined position, Fig. 2, against the pin o³ on the feeler. This swing-bar is rocked back and forth with the master feeler from its full to its dotted line position Fig. 3 at each pick.

Referring particularly to Fig. 2, o⁴ is a lug standing vertically from the weft slide C⁷, and o⁵ is an arm projecting forward from the end rail upon the lay and movable therewith, said arm having, as shown, an upturned end o⁶.

In the normal operation of the mechanism the full, unobstructed movement of the master feeler carries the swing lever o' always into one or the other of its extreme positions,

Fig. 3, clearing in its movement the arm o^5 , which latter is not of sufficient length to reach the lug o^4 when the lay reaches the end of its forward movement. When, however, the master feeler is obstructed in its movement, and is stopped after having begun such movement, it leaves the swing-lever midway between its two extreme positions, or in a substantially vertical position, Fig. 5, where it is retained frictionally by the spring n^x , said lever in its intermediate vertical position being interposed between the upturned end o^6 of the arm o^5 on the lay and the lug o^4 on the weft slide, so that when the lay approaches the end of its forward or beating-in movement the said arm o^5 will encounter the lower end of the swing-lever o' and through said lever will push the lug o^4 and the weft slide C^7 forward to effect the stopping of the loom. The rods n^5 , n^6 , are, as before stated, connected at their lower ends with the arms n^7 , n^8 , on the lay swords by chains or other flexible or suitable connections which provide a lost movement, whereby the master feeler is moved only at the last end of each forward and back movement of the lay.

The operation of my improved stop-motion may be briefly described as follows, viz:—So long as the wrap-threads remain unbroken and taut they will, when moved into the upper plane of the shed, exert a pull or tension upon the heddles which raise them, and will thereby draw said heddles and the pins or heads e^2 connected thereto down into their lowermost positions, as in Figs. 2, 3, and 6, so that the auxiliary feeler m of the heddle frame, which is raised, may have an unobstructed and free movement across the paths of movement of the said heads to thereby be turned to bring the finger m^2 on its arm m' into a substantially vertical position, Figs. 6 and 9. This is done just before the lay reaches the end of its backward movement, at which time the master feeler N , rocked by the actuating rods n^5 , n^6 , is moved on its pivots inwardly or toward the ends of the said heddle frames and the fingers thereon. The fingers on the raised heddle-frames standing in substantially vertical position by reason of the full movement of the auxiliary feeler described, permit said master feeler to have a full movement passing the fingers m^2 , the latter passing through the slots n^2 in the master feeler, such movement of the master feeler carrying the swing lever o' to the right, as in Fig. 3, into its dotted position beyond or out of the line of movement of the arm o^5 on the lay, so that as the latter approaches and reaches the end of its forward movement the upturned end of said arm will fall short of the lug o^4 on the weft slide and will fail to move the same, thereby permitting continued operation of the loom. If one of the warp-threads becomes broken or unduly slack it will fail to exert the proper tension upon the heddle which moves it and will permit said heddle to be retained taut by the action of the spring e^3

against the heddle-head keeping the said head in its raised normal position, as in Figs. 7 and 8. With the heddle-head in this position the movement of the auxiliary feeler on that heddle-frame is obstructed and stopped, leaving the finger m^2 on its arm m' in such an inclined position, as shown in Fig. 7 or Fig. 8, that it will not pass through its slot in the master feeler when the latter is moved toward it, the said finger when in such position stopping the master feeler midway the movement of the latter, after it has moved the swing-lever o' into a substantially vertical position, as in Fig. 5, directly in the line of movement of the arm o^5 on the lay. In its next succeeding forward or beating-in movement of the lay the end o^6 of the arm o^5 will strike the swing lever o' , interposed between it and the lug o^4 , and will push the said lever before it against and thereby moving the lug and the weft slide to effect the stopping of the loom, the said swing-lever turning on its pivot o to permit such movement, it being immediately returned to its position Fig. 2 upon the return movement of the master feeler. The lower end of the swing-lever o' , see Fig. 11, is formed at its front side adjacent the lug o^4 to present a concavity or recess, which when the lower end of the said lever is in contact with the said lug prevents the said lever being moved laterally away from the lug. This is necessary for the following reason, viz:—The master-feeler is, owing to the lost motion or slack in the rods n^5 , n^6 , moved only at the latter parts or ends of the forward or back movements of the lay. With this in mind, if the swinging lever has been stopped in its intermediate position by reason of a broken or slack warp-thread, as described, the arm o^5 will strike it as the lay approaches the end of its forward movement and will tend to push the same against and to move the lug o^4 to stop the loom, but as the master feeler is normally moved at or near the end of the inward movement of the lay, the tendency of the rod n^6 would be to pull the swinging lever out from between the arm o^5 and the lug o^4 before the slide-bar had been pushed sufficiently forward to stop the loom. This is prevented, as will be seen, by the recess o^x in the front side of the swinging lever, which prevents the latter being withdrawn from between the lug and the arm o^5 , so long as the said lever is maintained in contact with or against the lug. In the normal operation of the loom the swinging lever o' swings over and clears the arm o^5 behind the upturned end o^6 . For convenience in manufacture the heddle-heads e^2 are staggered in the bar d^x in order to make them as large as possible without requiring an undue amount of room.

The swing lever o' constitutes a connection, interposed at times between the movable lug o^4 which effects the stopping of the loom and the lay, a moving part of the loom.

In Fig. 10 I have shown one adaptation of

my invention to wire heddles of common construction, in which r is a part of a wire heddle, r' the heddle head and r^2 the spring to retain the same normally in an elevated position, but when wire heddles are used the heads r' may as well be formed as a part of the heddles themselves, as shown in Fig. 12.

As many heddle-frames as desired may be employed, for whatever be the number, a single master feeler is sufficient, it being necessary only that said master feeler be provided with as many vertical slots n^2 as there are heddle-frames; and it matters not how many of these heddle-frames be raised at once, for all or a part only may be raised and operate equally as well.

The term "heddle-heads," as employed in the claims, includes any heads either independent or forming a part of a heddle, and which are moved by the varying tension of the warp threads passed through the heddles.

This invention is not limited to the particular construction or parts herein shown, for the construction shown is simply one embodiment of this invention and such construction may be varied in many particulars without departing from the spirit and scope of the invention.

I claim—

30. 1. A warp-stop motion for looms containing the following instrumentalities, viz;—a heddle-frame, a series of heddles carried thereby, and heads connected with the said heddles and adapted to be moved by the varying tension of the warp threads therein, a feeler movable toward and from said heads, a co-operating master feeler, and a stopping mechanism controlled thereby, substantially as described.
35. 2. A warp-stop motion for looms containing the following instrumentalities, viz;—a heddle-frame, a series of heddles carried thereby, heads connected with said heddles and adapted to be moved by the varying tension of the warp threads therein, a feeler movable toward and from said heads, a co-operating master feeler, a stopping mechanism for the loom, a movable lug to actuate the same, and a connection actuated by said master-feeler and adapted to be at times interposed between said lug and a moving part of the loom to actuate the former by the latter, substantially as described.
40. 3. A warp-stop motion for looms containing the following instrumentalities, viz;—a series of heddle-frames, heddles carried by each, heads moved by said heddles, and auxiliary feelers on and movable with said frames, a master-feeler co-operating with said auxiliary feelers, and a stopping mechanism for the loom controlled by said master-feeler, substantially as described.
45. 4. A warp-stop motion for looms containing the following instrumentalities, viz;—a series of heddle-frames, heddles carried thereby, and heads connected with and moved by said heddles, a feeler on each of said heddle frames, a finger moved into different posi-

tions by said feeler, a master-feeler having openings to permit it to move past said fingers when the latter are in one position, and to be obstructed thereby when in other positions, and a stop-mechanism for the loom controlled by movement of said master-feeler, substantially as described.

5. A warp-stop motion for looms containing the following instrumentalities, viz;—a series of heddle-frames, heddles carried thereby; heads connected with and moved by said heddles; an auxiliary feeler on each of said frames; fingers on and movable by said auxiliary feelers; a master-feeler, having openings therein to co-operate with said fingers, a stopping mechanism; a movable lug controlling the same; and a movable connection on said master-feeler, and adapted to be moved into position between said lug and a moving part of the loom whereby said lug is actuated by said moving part of the loom, substantially as described.

6. A warp-stop motion for looms containing the following instrumentalities, viz;—a heddle-frame; heddles carried thereby; heads connected with and moved by said heddles; a co-operating pivoted feeler adapted to be swung toward and from said heads; and stopping mechanism for the loom controlled by movements of said feeler, substantially as described.

7. A warp-stop motion for looms containing the following instrumentalities, viz;—a series of heddle-frames; heddles carried thereby; heads connected with and moved by said heddles; auxiliary feelers on said heddle frames respectively; a lay and a master-feeler actuated therefrom and co-operating with said auxiliary feelers; and stopping mechanism for the loom controlled by said master-feeler, substantially as described.

8. A warp-stop motion for looms containing the following instrumentalities, viz;—a series of heddle-frames; heddles carried thereby; and heads moved by said heddles; a feeler; and an actuator therefor connected with a fixed support whereby movement of the said heddle-frame with relation to said support causes movement of said feeler, substantially as described.

9. A warp-stop motion for looms containing the following instrumentalities, viz;—a series of heddle-frames; heddles carried thereby; heads connected with and moved by said heddles; a feeler and a yielding actuator connecting the same with a fixed support whereby said feeler is moved by movement of said heddle-frame with relation to said support, said actuator yielding when movement of the feeler is obstructed, substantially as described.

10. A warp-stop motion for looms containing the following instrumentalities, viz;—a series of heddle-frames; heddles carried thereby; heads connected with and moved by said heddles; a feeler on each heddle frame and means to move the same; a co-operating master-feeler on the loom-frame; an actuator for the same

connected with and moved by the lay; and a spring interposed in said actuator; substantially as and for the purpose specified.

11. A warp-stop motion for looms containing the following instrumentalities, viz;—a series of heddle-frames; heddles carried thereby, and heads connected with and moved by said heddles; a feeler on each of said heddle-frames movable toward and from the heddle heads of their respective frames, a co-operating master-feeler, rods connecting the same with and to be actuated by the lay and to provide a lost motion whereby the feeler is moved only at or near the ends of the forward or back movement of the lay; stopping mechanism for the loom; a movable lug to actuate the same; and a connection actuated by said master-feeler and adapted to be at times interposed between said lug and a moving part of the loom to actuate the former by the latter, substantially as described.

12. A warp stop motion for looms containing the following instrumentalities, viz;—a series of heddle-frames, heddles carried thereby; heads connected with and moved by said heddles; an auxiliary feeler on each of said frames; fingers on and movable by said auxiliary feelers; a master-feeler, openings therein to co-operate with said fingers; a stopping mechanism; a movable lug controlling the same; a movable connection on said master-feeler

adapted to be moved into position between said lug and a moving part of the loom whereby said lug is actuated by said moving part of the loom; and a friction device for and to retain the said master-feeler and its connection in its different positions, substantially as described.

13. A warp stop-motion for looms containing the following instrumentalities, viz;—a series of heddle-frames, heddles carried thereby; heads connected with and moved by said heddles; an auxiliary feeler on each of said frames; fingers on and movable by said auxiliary feelers; a master-feeler, openings therein to co-operate with said fingers; a stopping mechanism; a movable lug controlling the same; and a movable connection σ' on said master-feeler and provided with a recess σ^x at its front side, the said connection being adapted to be moved into position between said lug and a moving part of the loom whereby said lug is actuated by said moving part of the loom, substantially as described.

In testimony whereof I have signed my name to this specification in the presence of two subscribing witnesses.

OBERLIN SMITH.
